CLAIM

The ornamental design for a self-adjusting bridging for floorboard joists, as shown and described.

DESCRIPTION

FIG. 1 is a top perspective front view of a self-adjusting bridging for floorboard joists, according to the present invention.

FIG. 2 is a top perspective view of the self-adjusting bridging for floorboard joists of FIG. 1.

FIG. 3 is a bottom perspective view of the self-adjusting bridging for floorboard joists of FIG. 1.

FIG. 4 is a partial enlarged view of FIG. 2 of the self-adjusting bridging for floorboard joists.

FIG. 5 is a front view of the self-adjusting bridging for floorboard joists of FIG. 1, shown in an open position.

FIG. 6 is a back view of the self-adjusting bridging for floorboard joists of FIG. 1, shown in an open position.

FIG. 7 is a left view of the self-adjusting bridging for floorboard joists of FIG. 1, shown in an open position.

FIG. 8 is a right view of the self-adjusting bridging for floorboard joists of FIG. 1, shown in an open position.

FIG. 9 is a top view of the self-adjusting bridging for floorboard joists of FIG. 1, shown in an open position.

FIG. 10 is a bottom view of the self-adjusting bridging for floorboard joists of FIG. 1, shown in an open position.

FIG. 11 is a front view of the self-adjusting bridging for floorboard joists of FIG. 1, shown in a closed position.

FIG. 12 is a back view of the self-adjusting bridging for floorboard joists of FIG. 1, shown in a closed position.

FIG. 13 is a left view of the self-adjusting bridging for floorboard joists of FIG. 1, shown in a closed position.

FIG. 14 is a right view of the self-adjusting bridging for floorboard joists of FIG. 1, shown in a closed position.

FIG. 15 is a top view of the self-adjusting bridging for floorboard joists of FIG. 1, shown in a closed position; and, FIG. 16 is a bottom view of the self-adjusting bridging for floorboard joists of FIG. 1, shown in a closed position.

The broken lines shown in FIG. 1 illustrate environment and form no part of the claimed design. The remaining broken lines shown in FIGS. 2-6 illustrate portions of the self-adjusting bridging for floorboard joists that form no part of the claimed design.
